BELT PROCESSING MACHINE

Otto Frederick Goepfert, Brevard, N. C., assignor
to Endless Belt Corporation, a corporation of
North Carolina

Application June 1, 1943, Serial No. 489,274

8 Claims.

(Cl. 69—1.5)

This invention relates to the manufacture of endless belting and more particularly but without limitation to a machine for finishing woven or otherwise fabricated, fibrous endless belts, by a combined stretching and ironing or calendering process after a certain organic or other chemical pretreatment in the course of production.

In the manufacture of endless belts woven or felted from cotton and other fibrous materials the belts are usually chemically treated to enhance their tractive qualities, make them wear resistant, moisture proof and otherwise resistant to deleterious effects of general atmospheric elements and extraneous local elements such as acids and oils to which the belts may be subjected in use. After their chemical treatment the belts are further processed to stretch, dry and set them to a definite size in some manner before they are placed in use.

An important object of the present invention is to provide for a practical, economical and highly efficient stretching of the pretreated belt to a predetermined, definite, finished size and at the same time drying and setting the belt to size by an ironing and calendering operation.

The invention consists in a machine of simplified yet practical and highly efficient construction and arrangement on which either a single belt or several at one and the same time can be processed with minimum attention and physical effort on the part of an attendant, which machine is readily operated and positive in action, as well as being of easy and inexpensive maintenance.

A practical but non-limiting embodiment of the invention is hereinafter described in connection with the accompanying illustrative drawings, in which:

Fig. 1 is a side elevation of the machine, showing two endless belts as placed thereon for the ironing and calendering operation;

Fig. 2 is a top plan view;

Fig. 3 is a longitudinal section, on an enlarged scale and taken on or about the line 3—3 of Fig. 2, through one of the power cylinders;

Figs. 4 and 5 are similar fragmentary views, more or less schematic in character, showing, respectively, the two operations of the foot-valve which controls the compressed air supply to and exhaust of the same from the power cylinder;

Fig. 6 is an end view of the machine;

Fig. 7 is a section, on an enlarged scale, taken on or about the line 7—7 of Fig. 2, showing details of the reciprocating carriage and its directly associated elements;

Fig. 8 is section through the gear housing, showing the details of the contained parts; and

Fig. 9 is a fragmentary view illustrative of a heating provision for the belt drying and calendering rolls of the machine.

Referring now to the illustrative drawings in detail, the numeral 10 designates a table or stand having legs or standards 11 by which it is supported on a floor or other substantial base. Mounted on the table or stand 10, adjacent one end thereof, is a housing 12. Also mounted on the table or stand 10 are longitudinal side frames 13 and a middle frame 14. Secured to and extending some distance beyond the outer ends of the frames 13 and 14 are rigid bars 15. Located between and securely fastened to these bars are elongated power cylinders 16. Interposed between and securely fastened to the outer end portions of the two cylinder supporting bars 15, which extend from the middle frame 14 are strut-blocks 17 that tie the two bars together and add to the rigidity of the structure.

Journalled in and extending transversely through the housing 12 and projected beyond the opposite side walls thereof, are parallel shafts 18 on the ends of which are fastened pulleys 19. These pulleys are provided to drive the endless belts (designated by symbol B) to be dried and ironed or calendered on the machine and said pulleys are heated in a manner to be later more specifically described. In the general use of the machine said pulleys are usually provided with plain, smooth, cylindrical, peripheral faces, but for some types of belting the circumferences of the pulleys may be knurled to give a counterpart surface finish to the processed belt, as well as affording a more positive tractive contact for driving the belt.

Opposed to the belt-driving pulleys 19 are idler pulleys 20 mounted on individual shafts 21 that are respectively carried by and project laterally from reciprocating carriages 22 riding on longitudinal track rails 23, respectively secured to the side frames 13 and middle frame 14. The track rails 23 are preferably formed with rack-teeth 24 (see Fig. 7) that are engaged by correspondingly toothed pinions 25 fixed on the opposite ends of a transverse shaft 26 journalled in bearing lugs 27 provided at the inner end of each particular carriage 22. This rack-and-pinion arrangement is to assure a straight-line reciprocation of the carriage and avoid binding of the carriage slide-way (shown conventionally at 28 in Fig. 7) on the track rails 23.

The idler pulleys 20 may or may not be heated.

Usually they are not heated because of structural complication that might arise due to the provision for a relatively long distance of travel of the carriage 22 and also because the main function of these pulleys 20, is in the stretching of the belts B as the drying is done by the driving pulleys 19, together with a stack of heated ironing and calendering idler rollers that are placed between the cooperating pulleys 19 and 20.

As shown, there is a set of ironing and calendering rollers on each side of the housing 12, each set comprising a stationary middle roller 29 mounted on a fixedly journaled shaft 29A, and opposed upper and lower rollers 30, 31, respectively, which latter are separately mounted on individual shafts 32 extending transversely of the housing 12 and journaled in bearing blocks 33 that are vertically movable in rectangular openings provided therefor in the side walls of the housing. The shafts 29A and 32 project some distance at either side of the housing 12 so as to support the respective rollers 29, 30 and 31 in substantial spaced relation to the housing (see Fig. 2). Any suitable provision and arrangement of springs (conventionally shown at 34 in Fig. 8) may be made for moving the upper bearing blocks upwardly and the lower bearing blocks downwardly against cam elements 35, also conventionally shown in Fig. 8.

Normally, the springs 34 press the bearing blocks 33 yieldably against the cam elements 35, and the space between the respective upper and lower rollers 30, 31, and the middle rollers 29, is sufficient to permit the belt B that is treated to be inserted easily between the peripheries of the middle roller 29 and the opposed roller 30 or 31, as the case may be. After the belt is thus placed between the ironing and calendering rollers and also placed on the driving pulley 19 and stretcher pulley 20, the cams 35 correlated to that particular roller 30 or 31 are rotated so that their high portions engage the adjacent bearing blocks 33 carrying the shaft 32 of such roller so as to move the roller towards the stationarily mounted roller 29. For this purpose the respective cams 35 are fixed on transverse shafts 36 journaled in stationary bearings provided therefor in the opposite side walls of the housing 12. One end portion of the shaft 36 adjacent the correlated roller 30 or 31 is extended some distance outside of the housing 12 and provided with an operating lever 37 having a crank-handle 38 thereon. It is, of course, understood that there is a bearing block 33 mounted slidably in each side wall of the housing 12 for each shaft 32, and there are two corresponding cams 35 on each shaft 36, one cam in direct cooperative relation to each bearing block 33. It is further noted that the two vertically aligned shafts 32 that carry the opposed rollers 30 and 31 at one side of the machine are offset laterally out of vertical coincidence with the two other shafts 32 that carry the opposed rollers 30 and 31 at the opposite side of the machine. So, too, of course, are the respective pairs of correlated upper and lower controlling cams 35 of the bearing blocks 33.

In correlation to each operating lever 37 there is a fixed stop 39 on the housing wall, against which the lever is stopped in its movement in the direction to permit the lifting of the roller 30 or 31 from the middle roller 29. Opposed to this stationary stop 39 is an adjustable stop 40 for arresting the operating lever 37 in its movement in the direction to effect the closing of the roller 30 or 31 upon the belt B as supported by the

opposed middle roller 29. Thus, by adjusting the stop 40 to limit the throw of the cam lever 37 the desired compression is placed the belt where it is positioned between the fixedly mounted roller 30 or 31, as the case may be, for a given finished thickness of the belt.

The ironing and calendering rollers 29, 30 and 31, are each hollow, like the driving pulley 19 and they, too, are heated. The heating of all of these rollers and pulleys is illustrated conventionally in Fig. 9, wherein an annular gas-burner-head 41 is supported by a gas supply pipe 42 within the hollow pulley 19 and surrounding the hub thereof. As shown more or less diagrammatically in Fig. 1, the several gas supply pipes 42 to the respective pulleys and rollers 19, 29, 30 and 31, lead from a manifold 43 and each pipe is provided with a stop-cock or valve 44. The gas from the source (not shown) is supplied to the manifold 43 through the main supply pipe 45 having a stop-cock or valve 45A.

Inasmuch as the normal space between the calendering rollers 29, 30 and 31 is only slightly greater than the maximum thickness of belts to be ironed, and the necessary movement of the rollers 30 and 31 toward and from the stationary roller 29 to effect the ironing of the belts is also comparatively slight, the interior diameter of the annular gas-burner-head 41 is usually large enough to afford ample play between said element 41 and the shaft 32 without any undue flexing or straining of the gas supply pipe 42. However, should more up and down movement of the rollers 30 and 31 be required, the inherent flexibility of the angular pipe extension will generally permit of such movement, or, obviously, a special substantially flexible pipe section or a hinged coupling may be incorporated in the piping 42 adjacent the shafts 32 in any conventional manner.

A conventional gearing is provided, as illustrated in Fig. 8, for positively rotating the driving pulleys 19 from a single motor which is indicated at 46 in Fig. 1. The motor pulley 47 is belted, as at 48, to a driven pulley 49 on a main power shaft 50 having a spur gear 51 fixed thereon within the housing 12. The gear 51 is in mesh with an idler gear 52 that has a pinion 53 fixed to rotate therewith on a shaft 52A. The pinion 53 drives a larger gear 54 that has a sprocket wheel 55 fixed to rotate therewith on a shaft 54A, said sprocket wheel 55 driving a larger sprocket wheel 56 by the chain 57.

Rotatable by and with the sprocket wheel 56 on a shaft 56A is an intermediate gear 58 that drives opposed gears 59 and 60 respectively fixed on the shafts 18 carrying the belt-driving pulleys 19. By this particular provision and arrangement the four driving pulleys 19 (two on each side of the machine) are rotated simultaneously and at the same speed, and constantly during the operation of the illustrated machine. However, in some machines, provision may be made, within the purview of the invention, for operating the several belt-driving pulleys 19 separately and independently of each other. But for general use it has been found practical to have the several belt-driving pulleys 19 rotate simultaneously and constantly, particularly in the machine of the duplex type as illustrated, i. e., a machine wherein two sets of cooperating driving pulleys 19 and idler pulleys 20 are provided on each side of the machine.

In the machine as illustrated in the drawings, the reciprocating carriages 22 are adjustably at-

tached to the pistons of the respective power cylinders 16. As shown more clearly in Figs. 3 and 7, the piston 61 has an elongated stem 62 extended a substantial distance from the cylinder head and has its forward end portion screw-threaded for a considerable length thereof, as at 63. This threaded portion of the piston stem is screwed into a correspondingly threaded bore in a depending lug 64 on the carriage 22, jam nuts 65 being provided on the stem and tightened against opposite sides of the lug for locking the latter in its adjusted position on the stem. In this way the carriage 22 is adjustable for the processing of belts of different lengths and it is moved by and in the same direction with the piston, accordingly as the fluid pressure (compressed air in illustrated exemplification of the invention) is admitted to the cylinder 16 at either side of the piston 61.

The details of the preferred practical power cylinder construction and the operation of the piston therein are illustrated in Fig. 3. As shown, the cylinder body 16 is provided with a head 66 bolted thereto at its outer end in a conventional manner, this head having an axial port 67 where a compressed air supply pipe 68 is attached. When air pressure is supplied to the cylinder through the pipe 68 and the piston is thereby moved forwardly, the stroke of the piston is cushioned adjacent the head 66 at the inner end of the cylinder. This cushioning effect is accomplished by forming an axial, circular, recess 70 in the cylinder head 66 to receive, with an easy, sliding fit, a boss or hub extension 71 of the piston 61, said recess 70 being in constant communication with a compressed air supply pipe 72 through a passageway 73 in the piston head. Communicating with the passageway 73 is a restricted angular port 74 that opens into the power cylinder 16 and is controlled by a spring-pressed ball-check-valve 75 that normally closes the port so as to prevent outflow of fluid from the power cylinder but is yieldable to permit inflow of fluid into the power cylinder from the supply pipe 72. By the foregoing provision, when the piston 61 is forced forwardly under the air pressure in the cylinder as supplied from the supply pipe 68, the air in the cylinder ahead of the piston is forced out through the recess 70 and passageway 73 in the cylinder head 66 and into the supply pipe 72, which pipe, as will be later more specifically described, is at the time cut off from the source of air supply and is opened to an exhaust. This exhaust of air ahead of the piston continues until the boss or hub extension 71 of the piston enters the recess 70, whereupon further outflow of air from the cylinder is prevented because of the closing of said recess 70 by the boss or hub extension 71 and the ball-check-valve 75 at the same time effectively closing the port 74. The air remaining in the cylinder after this stoppage of outflow is compressed between the cylinder head and the piston and thus stops piston travel with a cushioning effect.

When the belt B to be stretched and ironed or calendered is placed on the driving pulley 19 and the idler stretcher pulley 20 as hereinbefore described, an adjustable stop 76 is set to limit the travel of the carriage 22 that carries the pulley 20, the setting of said stop 76 being determined for the stretching of a belt to given length size. With the stop thus set, the air supply pipe 68 is opened to exhaust and compressed air is supplied to the power cylinder 16 through the supply pipe 72. The piston 61 then being in

its forward position in the cylinder with the boss or hub extension 71 within the recess 70 of the cylinder head, the compressed air initially enters the cylinder through the restricted port 74. Then, after the piston has moved, under pressure of the restricted compressed air supply, a distance sufficient to withdraw the boss or hub extension 71 from the recess 70 in the cylinder head 66, the full force of the compressed air entering the cylinder through the passageway 73 and recess 70 drives the piston 61 more rapidly and powerfully towards the outer end of the cylinder. No special cushioning provision is provided in the cylinder for this outward stroke of the piston. The cushioning is accomplished by the tautening and stretching of the belt B on the pulleys 19 and 20 which effectively checks the travel of the piston just prior to the stopping of the traveling carriage 22 against the set stop 76, thus avoiding shock and damage that might otherwise occur by an abrupt and sudden stoppage of carriage and piston in their travel.

As illustrated more clearly in Figs. 6 and 7, the carriage stop 76 comprises an upper cross-bar that rests at its ends on the track rails 23 and it is rabbeted and provided with teeth 77 (see Fig. 7) to engage the rack-teeth of the adjacent track rails. Beneath the bar 76 is a parallel clamping bar 78 having rabbeted end portions 79 to engage under the adjacent track rails. The rabbeting of the bars 76 and 78 prevents end-wise movement of the bars when engaged with the track rails 23. The bars are releasably held in engagement with the rails 23 by a screw element 80 having a knurled head or any other conventional provision for its manipulation to loosen and tighten the bars 76 and 78 in effecting the various adjustments of the carriage stop.

For the control of the compressed air supply to the several power cylinders 16 and exhausting the same during the operation of the machine, foot valves 81 are provided as conventionally indicated in Figs. 1, 4 and 5. There is one of these valves for each power cylinder in the illustrative machine. Leading into each valve 81 there is a supply pipe 82 from a common main supply pipe 82A leading from a source of compressed air supply (not shown). The main supply pipe 82A is provided with a conventional controlling and cut-off valve 82B. The several other pipes in the compressed air supply system of the machine may be individually provided with customary stop-cocks and controlling valves, but as the same are quite obvious and do not enter into the present invention such provision is not illustrated in the drawings.

The foot valves 81 (or their equivalent) are essential and they are accordingly illustrated, although more or less conventionally. As shown in Figs. 4 and 5, the valve casing is conventionally circular and leading into one side thereof is the pipe 82 from the source of compressed air supply as just above described. At a right angular point the pipe 82 is communicably attached to the valve casing and leads to the outer end of one of the power cylinders 16. At a diametrically opposite point the pipe 72 is communicably attached to the valve casing and leads to the inner end of the same power cylinder.

Each valve casing 81 has two exhaust pipes 83, 84, one correlated to the supply pipe 68 and the other correlated to the supply pipe 72. Both pipes 83, 84 of each valve 81 are communicably connected to a common main exhaust pipe 85. The main exhaust pipe 85 is extended to terminate

within the lower portion of the hereinbefore described gear housing 12 (see Figs. 1 and 8) so that the air is discharged into the housing and thus serves as a cooling medium for the gears within the housing which become heated during the operation of the machine, not only from the friction in their working contact with each other but also from the transmitted heat that is applied to the driving pulleys 19 and the ironing and calendering rolls 29, 30, and 31.

Each valve 81 includes an internal, rotary, two-way, by-passing member 86 having a pair of reversed passageways 87, 88, arranged and adapted to alternately establish communication between the main supply pipe 82 and either the pipe 68 or the pipe 72 leading to the power cylinder 16. The passageways 87, 88 are also proportioned so that when one of the pipes 68 or 72 is in communication with the air supply pipe 82 the other is in communication with the exhaust pipe 83 or 84, as the case may be.

The rotary member 86 of each valve 81 is provided with a lever extension having a foot-pedal 89 at the outer end thereof, and this lever extension is yieldably held in a normally raised position and returned to such position after each successive actuation by a spring element 90. In the raised position (see Fig. 4) the compressed air supply pipe 68 is opened to supply the fluid pressure to the power cylinder 16 and the other supply pipe 72 is opened to communication with the exhaust pipe 84. When the foot-pedal is depressed (see Fig. 5) the compressed air supply pipe 72 is opened to supply the fluid pressure to the cylinder 16 and the other supply pipe 68 is opened to communication with the exhaust pipe 83.

A latch element, as indicated at 91 in Figs. 4 and 5, may or may not be employed to releasably hold the foot-pedal 89 in lowered position, as desired.

In the operation of the machine all that is physically required on the part of the operator is to first set the stop 76 to limit the travel of the carriage 22 for the desired length dimension of the belt B to be processed on the machine. Then place the pretreated endless belt or belts on the driving pulley or pulleys 19 and the companion idler pulley or pulleys 20 of the carriage or carriages, depending upon the number of belts to be processed at the same time. After the belt or belts are thus placed the foot-pedal 89 of the controlling valve 81 for the compressed air supply is depressed and so held, either by the foot of the operator or the latch element 91 (if the latter is provided) until the drying and ironing or calendering is effected. The ironing and calendering rollers 29, 30 and 31 may be relatively set to press the belt passing therebetween either before or after the belt is stretched between the driving and idler pulleys.

After the processing operation on the belt or belts is completed, the foot-pedal is permitted to rise and the controlling valve accordingly actuated to reverse the supply of compressed air to the power cylinder, whereby the carriage is restored to normal inactive position and the processed belt or belts thus loosened and slackened between the supporting pulleys. The ironing and calendering rollers are then moved apart to relieve the belt or belts of the roller pressure and the belt or belts next removed from the machine. Thereafter, the same belt processing operations are carried out successively and expeditiously on the machine, and to material advantage on a large commercial scale. By the provision of a

foot-pedal control of the air supply valves 81 instead of a hand-operated valve, both hands of the operator are free for the handling of the belts and manipulation of the essential normally operable parts of the machine.

The machine herewith illustrated and described represents a practical but non-limiting embodiment of the invention. Therefore, substantial alteration and modification is contemplated within the spirit of the invention and scope of the appended claims.

I claim:

1. In a machine for processing endless belts, opposed pulleys spaced apart and one pulley movable towards and away from the other, and at least one of the pulleys being heated, power means for rotating at least one of the pulleys, controlled power means for moving the movable pulley in either direction relative to the other pulley at the will of an operator, adjustable stop means for selective limitation of movement of the movable pulley away from the other pulley whereby an endless belt supported and traveling on said pulleys is stretched to a definite predetermined length dimension, and opposed, heated, calendering rollers between which the belt on the said pulleys is passed under pressure exerted by said rollers.

2. In a machine for processing endless belts, a power-actuated driving pulley and a cooperatively opposed idler pulley on which an endless belt to be processed is supported and travels, a reciprocating carriage carrying said idler pulley, a fluid pressure power cylinder having a reciprocating piston therein, a connection between said piston and said carriage whereby travel of the one is imparted to the other, means within said power cylinder for cushioning the piston therein at the end of its stroke in the direction to move the carriage toward said belt supporting and driving pulley, an external adjustable stop element for varying and limiting the travel of said carriage in the direction away from said belt supporting and driving pulley, and controlled means for supplying fluid pressure to said power cylinder selectively at either side of the piston and at the same time exhausting the fluid pressure from the cylinder at the side of the piston opposite to that at which the fluid pressure is being effectively applied.

3. A machine for processing endless belts comprising means for supporting and stretching a belt to a given length dimension and at the same time causing travel of the belt, opposed calendering rollers, the one relatively movable toward the other and between which rollers the belt supported and traveling on said supporting and stretching means travels, and adjustable means for positively moving and setting the movable one of said calendering rollers toward the other whereby to press to a given thickness the belt traveling between the rollers.

4. In a belt processing machine, a power-actuated, heated, driving pulley and a cooperatively opposed idler pulley on which an endless belt is supported and caused to travel, one of said pulleys being movable toward and away from the other, controlled power means for selectively moving the movable pulley in either direction at the will of an operator, normally spaced, cooperatively opposed, heated, ironing and calendering rollers, the one movable with relation to the other and between which the supported belt is passed in its travel between said first mentioned pulleys, and means including a cam element, a cam operating

and holding element and an adjustable stop limiting the movement of said cam operating and holding element, for setting and holding said ironing and calendering rollers in a definitely spaced relation to each other whereby to press the belt passing therebetween to a desired thickness.

5. The processing of an endless belt, comprising the placing of the belt supportedly on cooperatively opposed pulleys, rotating the pulleys with the belt thereon whereby to cause the belt to travel accordingly about the pulleys, forcibly spacing the pulleys to a definite predetermined distance apart during the time the belt is carried thereon, whereby to stretch and set the belt to a desired finished length dimension and passing the stretched belt as it is caused to travel around said pulleys between transversely arranged and cooperatively opposed ironing and calendering rollers whereby the belt is pressed to a predetermined uniform thickness throughout.

6. The processing of a pretreated endless belt, comprising the placing of the belt supportedly on cooperatively opposed pulleys, at least one of which is heated, rotating the pulleys with the belt thereon, whereby to cause the belt to accordingly travel about the pulleys, forcibly spacing the pulleys to a definite predetermined distance apart during the time the belt is carried thereon, whereby to stretch and set the belt to a desired finished length dimension, and, during its travel on said

supporting and stretching pulleys, passing the belt between heated, cooperatively opposed, ironing and calendering rollers, whereby the belt is pressed to a predetermined thickness.

7. In a machine for processing endless belts, opposed pulleys spaced apart, means for rotating at least one of said pulleys, controllable means for varying the spacing of said pulleys, adjustable stop means for selective limitation of the extent to which said pulleys may be spaced apart whereby an endless belt supported and traveling on said pulleys is stretched to a predetermined length dimension, and opposed calendering rolls between which the belt on said pulleys is passed whereby said belt is pressed to a given thickness.

8. In a machine for processing endless belts, opposed, spaced apart, pulley members, said pulley members comprising pulleys mounted at each end of an intermediately journaled shaft, means for rotating at least one of said pulley members, controllable means for varying the spacing of said pulley members, adjustable stop means for selective limitation of the extent to which said pulley members may be spaced apart whereby endless belts supported and traveling on said pulleys are stretched to a predetermined length dimension, and opposed calendering rolls between which the belts on said pulley members are passed, whereby said belts are pressed to a given thickness.

OTTO FREDERICK GOEPFERT.
